UNITED STATES PATENT OFFICE.

FRANK W. BOYD, OF SPOKANE, WASHINGTON, ASSIGNOR OF ONE-THIRD TO JOSEPH A. O'CONNELL, OF SPOKANE, WASHINGTON.

FUSE PLUG.

1,416,602.

Specification of Letters Patent. Patented May 16, 1922.

Application filed August 12, 1919. Serial No. 318,303.

To all whom it may concern:

Be it known that I, FRANK W. BOYD, a citizen of the United States, residing at Spokane, in Spokane County and State of Washington, have invented certain new and useful Improvements in Fuse Plugs, of which the following is a specification.

The present invention relates to improvements in fuse plugs of the quick, detachable, screw plug type of connector, and is designed to provide a plug of this character in which the fuse may be readily removed after a blow out and a fresh one installed without the necessity of removing the entire plug, and means are also provided whereby the gases of combustion are permitted to escape after the fuse has been burned.

The invention consists in certain novel combinations and arrangements of parts as will be hereinafter more fully and specifically pointed out in the following claims.

In the accompanying drawings one complete example of the physical embodiment of the invention is illustrated the parts being combined and arranged according to the best mode I have so far devised for the practical application of the principles of my invention.

Figure 1 is a side view of a fuse plug embodying the novel features of the invention.

Figure 2 is a vertical sectional view of the plug.

Figure 3 is a top plan view of the plug base.

Figure 4 is a side view of the stem and fuse detached.

Figure 5 is a sectional view of the top disk for the base.

In the preferred form of the invention as illustrated in the drawings the usual and standard porcelain plug base 1 is externally threaded to receive the shell or casing 2 which also is threaded as usual, and the upper open end of the base is closed by means of the closure or top disk 3, made of insulation material and circular in form as shown. The top or disk is held to the base by means of the metal cap 4 having the turned in annular flange 4' which fits under the annular shoulder 5' of the base and secures the disk rigidly and securely in position. The disk is open at its center and its walls at the center are screw threaded with a metal lining 5 to receive the fuse stem 6 which has an upper threaded portion 7 to

engage and be threaded into the disk, a head 8 on the stem being provided for turning the stem into place. The fuse 9 is incased within a groove in the face of the stem 6 as usual and has at its lower end the terminal 10 formed as a ball which is adapted to fit into the socket 11 that is fashioned on the fixed contact head 12 at the lower end of the plug, the connector thus being formed similar to a ball and socket or glove fastener of the snap type, well known in use. The fuse ribbon is thus soldered at one end to the threaded, brass, portion of the stem at one end, and at its other end to the ball member, the detachable stem being completed with the inclusion of the head 8 by which it may be manipulated.

The stem thus is held by its connection at one end with the contact head 12 through the ball and socket joint making a snap joint, and at the other end by the screw threaded connection between the stem and the disk 3, which as before stated is insulation material. In this manner the fuse may be quickly replaced if necessary by inserting the ball end of the stem through the opening in the disk and passing the stem through the hollow base block or member, and snapping the ball and socket members together in manner well understood.

The metallic conductor 13 forming connection with the socket member of the disk 3 is accommodated by a slot 14 in the upper part of the base, and this conductor is welded or soldered to the lining 5 of the disk and extends outwardly into contact with the shell 2 of the plug. To protect the conductor from the flame or blaze that might flash up in the plug, an integral overhanging tongue 15 is provided to shield conductor as it lies in the slot 14 provided for it, and preferably, vent openings 16 are provided in the top of the base of the plug as shown in Figure 3, extending out radially, under the disk or cover of the plug. The plug is screwed into the socket in usual manner, and the engagements are made with the contacts in the socket or receptacle through the contact shell and contact head in well known manner.

From the above description taken in connection with my drawings it is evident that I have provided a fuse plug that, by its construction and arrangement of parts attains results in a more satisfactory and eco-

metallic conductor strip extended from the cover to the shell, and means for shielding said strip for the purpose described.

- 15 2. The combination in a fuse plug with a hollow base member having an inwardly projecting integral tongue and an open slot, and a cover having a threaded central opening, of a fuse stem threaded in said opening, 20 a fuse in the stem, an exterior shell on the base member, a metallic conductor strip extended from the central opening of the cover

having an inwardly flange under said shoulder, a fuse stem threaded in said threaded opening and a fuse in the stem, an exterior contact shell on the base member, a metallic conductor strip extended from the threaded opening of the cover through the open slot to the contact shell, a ball on the end of the fuse stem, and a contact head seated in the base member having a socket to receive said ball.

In testimony whereof I affix my signature.
FRANK W. BOYD.
